UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,282,844.

Specification of Letters Patent. Patented Oct. 29, 1918.

Application filed June 23, 1917. Serial No. 176,483.

To all whom it may concern:

Be it known that I, ARTHUR A. JOHNSON, a citizen of the United States, residing in borough of the Bronx, in the county of the Bronx, city and State of New York, have invented certain new and useful Improvements in Type-Writing Machines, of which the following is a specification.

This invention relates to an improvement 10 in typewriting machines, and more especially to an attachment known as the fan-fold, for typewriting simultaneously a plurality of copies of the same piece of work, and repeating the operation continuously for 15 a number of pieces of work of like character. The invention is shown as applied to an Underwood typewriting machine.

In the present disclosure of the invention, the work-sheets are fed around the platen 20 from continuous strips and cut off after being completed. The sheets are interleaved by carbon sheets, so that the writing on the uppermost sheet may be copied onto the other sheets. Inasmuch as the carbon sheets 25 may be repeatedly used for a large number of separate pieces of work, and one object of the present invention is to provide for such repeated use, it is necessary to space the work-sheet strips relatively to the carbon sheets. This is done in the present case 30 by withdrawing the pack, comprising the intermingled carbon work-sheets, to a position clear of the platen, so as to eliminate the bend around the platen, and thus lessen 35 the friction between the carbon sheet and the work-sheet. Then the work-sheets are advanced relatively to the carbon sheets to bring a fresh surface of the work-sheet webs into register with the carbon sheets. The 40 pack comprising the carbon sheets and the new portions of the work-sheets is then advanced as a unit to a position around the platen ready to be written upon.

The carbon sheets are herein shown as 45 mounted on rolls off to one side of the line of travel of the work-sheet webs or strips, and are turned at right angles to a position to extend in line with the work-sheet webs.

Guide plates, having edges placed at 45 50 degrees with respect to the line of travel of the work-sheet webs, turn the carbon sheets and interleave them between the work-sheet strips. The carbon rollers are connected to be driven positively from the platen, so that 55 the carbon sheets will move in unison with

the platen both in feeding forward with the platen and in withdrawing them from the platen. Feed-rolls for the work-sheets are also connected to be driven from the platen, so that the work-sheets 60 may be withdrawn with the carbon sheets. Thus, the carbon sheets and the work-sheets, when being withdrawn prior to a spacing action, may be driven from three points in unison. 65

The spacing of the work-sheets relatively to the carbon sheets is herein shown as accomplished by locking the drive to the carbon rolls, and releasing the drive from the work-sheets, at the same time releasing the 70 pressure feed rolls from the platen. Under these circumstances, the work-sheet web or strips can be drawn forward by hand relatively to the carbon sheets, which are held stationary. 75

A knife is provided for cutting off the work-sheets from the continuous strips after the writing has been completed. This knife is made shiftable so as to permit access to the top edges of a completed pack of work-sheets, so that the work-sheets can be drawn on by hand to properly space and position the work-sheets and carbon sheets. This withdrawal of the knife is accomplished by the releasing of the pressure feed rolls, to enable the pulling on the work-sheet to take place when the rolls are cleared from the platen. 85

A gage is herein shown as provided some distance above the knife, to which the top 90 edges of the work-sheets can be drawn, to determine the length of work-sheet to be cut off. The knife is adjustable to vary the length of the work-sheet, and the gage is also adjustable. A guide is shown as provided for deflecting the work-sheets from the gage during a normal typewriting action, and this guide is depressed out of the way to permit the use of the gage when the mechanism is adjusted for withdrawing a 100 completed work-sheet from the platen and gagging the same.

Other features and advantages will hereinafter appear.

In the accompanying drawings, 105
Figure 1 is a front view in elevation, showing the platen and the work-sheet cutting and gaging means, and the driving mechanism for moving the work-sheets and carbon sheets in unison with the platen. 110

Fig. 2 is a detail view of the intermittent stop for gaging the advancing movement of the pack of carbon and work sheets as driven by a hand crank which will bring the initial line to be written on to the printing point of the typewriter.

Fig. 3 is a top plan view, showing the relation of the carbon roll and carbons thereon to the work-sheets, and the means for interleaving them between the work-sheet strips.

Fig. 4 is a similar diagrammatic perspective view, showing the manner of interleaving the carbon sheets between the work-sheets.

Fig. 5 is a view in side elevation, showing the general control of the feeding mechanism for the work and carbon sheets, and showing in full and dotted lines the position of the clearing guide when normally typewriting and when receded to permit gaging of the work-sheets respectively.

Fig. 6 is a detail view in vertical section, taken from front to rear, showing the carbon and work-sheet strips as having been withdrawn, after the writing of a piece of work, such as a bill, to a position removing the kink or bend in the pack, and with the parts of the driving and feeding mechanism arranged to permit a withdrawal of the work-sheets forwardly, so as to advance them relative to the carbon sheets.

Fig. 7 is a view taken similar to Fig. 6, except that the assembled pack of intermingled work and carbon sheets have been advanced to a full bill space, showing that the piece of work, such as a bill, has been completed. This corresponds to a condition of the parts just prior to that of Fig. 6.

The platen 1 about which the assemblage or pack of interleaved carbon and work-sheets is partly wrapped or turned during a typewriting operation, is secured to an axle 2 mounted to rotate in a platen frame 3, which is mounted in the usual manner on the typewriter carriage. The platen 1 may be line-spaced in the usual manner by means of a line-space lever 4, which advances the platen a line at a time, carrying with it the work and carbon sheets.

In order that the pack comprising the work and carbon sheets may be gripped to the platen 1, so as to feed therewith, there are provided pressure feed-rolls 5 and 6 of the usual type. These feed-rolls are mounted on swinging arms 7 and 8 pivoted on a shaft 9. The arms 8 and 7 have other arms 10 and 11 connected to them respectively, and these arms engage on opposite sides of a rock shaft 12. The rock shaft 12 is squared at the point where the arms 10 and 11 engage it, so that when it is rocked, it will spread these arms apart, thus withdrawing the pressure feed-rolls 5 and 6 from engagement with the work-sheets on the platen

1, against the tension of springs, not shown. The rock shaft 12 is operated by a crank 13, which, in turn, is operated by a thrust link 14 connected to an arm 15 of a release key 16. The release key 16 is in the form of a finger-piece and is depressed in the usual manner to spread the rolls 5 and 6. This finger-piece, as will be described hereinafter, performs other functions connected with the control of the work and carbon sheets.

The work-sheets, connected at 17, are in the form of continuous strips coming from a roll or separate rolls, or a receptacle, not shown, and passing over the guide roll 18. From the guide roll 18, they extend between 80 guiding or feeding rolls 19 and 20, mounted on axles 21 and 22. The strips 17, from which the work-sheets are cut, pass from the rolls 19 and 20 outside of and between guide plates 23, 24, 25 and 26. These guide plates 85 separate the sheet strips 17, so that carbon sheets 27 may be interleaved between them, enabling the typewriting on one sheet to be reproduced on the other sheets.

The guide plates 23 to 26 are triangular in form, as best seen by reference to Fig. 3, and have guiding edges 28 arranged at angles of 45 degrees with the line of travel of the work-sheet strips 17. These guide plates alternate in their position so that where one 95 has its guiding edge extending from right to left, the next adjacent has its guiding edge extending from left to right. This is to accommodate the direction from which the carbon sheets come to their positions between 100 the work-sheet strips 17. That is to say, the carbon sheets 27 are mounted on rolls 29, one roll for each carbon sheet, and the rolls for the carbon sheets are located alternately on opposite sides of a frame 30 which carries 105 the guide plates 23 to 26. The carbon rolls 29 are rotatably mounted by means of axles 31 journaled in auxiliary frames 32 and 33 projecting sidewise from the main frame 30.

The carbon rolls 29 are detachably mounted, so that they can be removed to replace worn out carbon sheets with fresh ones. For this purpose, the axles 31 are inset in drive shafts 34 at one end and are connected by pin-and-slot splines 35, so as to rotate with 110 these shafts. The other end of each axle 31 is set in a socket 36, and held in the socket by means of a latch 37, which may be swung to one side to permit the removal of the associated carbon roll. In the present instance, 115 five work-sheets are shown, corresponding to the making of five copies of one piece of work, which requires four carbon sheets, so that there are two carbon rolls on each side of the main frame 30.

In order to drive the work-sheet strips and the carbon sheets at the same time as the platen is driven, so that the rear portions of the work and carbon sheets may keep pace with the movement of those portions 120

of the sheets which are wrapped around the platen, the platen axle 2 is provided with a bevel gear 38, which meshes to drive a bevel gear 39 secured to a shaft 40 extending rearwardly of the frame 30. At the rear end of the shaft 40, there is provided a bevel gear 41 which meshes with a bevel gear 42 to drive a vertical shaft 43. The vertical shaft 43 has a bevel gear 44 driving a bevel gear 45 on a horizontal shaft 46, extending to a position about midway of the frame 30. At this point, the horizontal shaft 46 is provided with a bevel gear 47 meshing with a corresponding gear 48 on a vertical shaft 49. On this vertical shaft 49, there is provided a pinion 50, which meshes with a pair of driving rack bars 51 and 52 which are oppositely facing, so as to engage the pinion 50 at opposite sides. The pinion 50 can thus spread or retract the guide rack bars 51 and 52, according to the direction of rotation of the platen 1. In addition to the racks which mesh with the pinion 50, the drive rack bars 51 and 52 have auxiliary racks on their under sides at 53 and 54 to mesh with and drive four pinions 55, one on each of the carbon roll shafts 34.

The carbon sheets 27 are wrapped around the rolls 29 in such a manner, and the driving train from the platen axle 2 is so arranged, that the carbon sheets will be fed in the same direction at the carbon rolls as they are at the platen. In this way, the carbon sheets can keep pace with the line-space and advancing movement of the platen, and also can withdraw the carbon sheets from the platen as the latter is reversely rotated.

In addition to driving the carbon rolls from the platen, the rear work-sheet feed rolls 19 and 20 are also driven from the platen. For this purpose, the shaft 40, Fig. 5, is provided with another bevel gear 56, which drives a bevel gear 57. The bevel gear 57 has secured to it, for rotation therewith, a pinion 58 which drives a pinion 59 secured to the axle 22 for the work-sheet feed roll 20. The other feeding roll 19 for the work-sheet strip is normally pressed toward the roll 20 by means of one or more springs 60, which engage sliding blocks 61 forming floating bearings for the axle 21. In this way, the two rolls 19 and 20 normally grip the work-sheet strips 17, so as to advance them with the advancing movement of the platen, and may also act to withdraw the work-sheet strips from the platen with a reverse rotation of the platen when taking out the bend in the pack of assembled sheets.

When it is desired to withdraw the work-sheet strips by hand, the roll 19 may be moved to an inactive position by means of a pair of shifting cam arms 62 secured to a shaft 63. These arms raise the roll 19

against the tension of the springs 60 and hold it in its raised position until released. The arms 62 are operated from the release finger-piece 16 as the feed rolls at the platen are also released, when it is desired to draw the work-sheets forward by hand. For this purpose, the rock shaft 63 is provided with an arm 64 connected by a link 65 to the bell crank of the finger-piece 16. Inasmuch as the driving train is preferably locked when the sheets are so withdrawn while the feed rolls 19 and 20 are released, there is provided a dog 66 arranged to be swung into engagement with the teeth of the gear 59 when the pressure rolls 5, 6 and 19 are rendered inactive. This dog 66 is pivoted to one of the arms 62 and yieldingly held to its work by a spring 67, so as to prevent breakage of the parts in case it should engage on the end of one of the teeth of the gear 59.

In addition to driving the platen 1 by the line-space lever 4, it may also be driven both reversely and in an advancing direction a major amount, so as to withdraw the pack 90 of work-sheets and carbon sheets, displace them, and return them to the platen. For this purpose, the platen axle 2 is provided, at the opposite end from which the gear 38 is mounted, with a pinion 68 arranged to be engaged and driven by a gear segment 69. The gear segment 69 is mounted on a hand-crank 70 pivoted intermediate its ends at 71. By pulling the hand-crank 70 forward, the platen 1 is rotated in an advancing direction, and for the reverse movement of the platen, the hand-crank 70 is forced rearwardly at its upper end.

A portion of the movement of the hand-crank 70 is set off for the purpose of covering the distance from a sheet guide-roll 72 to the printing point 73 on which type-bars 74 strike the work-sheet on the platen. That is to say, when the pack comprising the interleaved work-sheets and carbon sheets is withdrawn reversely from the platen for spacing purposes, the leading edges of the carbon sheets will come to a point indicated at 75, Fig. 6, just behind the roll 72. After new portions of the work-sheets have been brought in register with the carbon sheets the work-sheets and carbon sheets are brought around to a position where these leading edges of the carbon sheets are just above the printing point 73.

In order that this portion of the motion of the rotation of the platen and the motion of the hand-crank 70 may be automatically determined, there is provided an intermittent gage stop, Fig. 2. This stop comprises a plunger 76 guided against rotary movement and sliding through the body portion of the gear segment 69. On one end, the plunger 76 is provided with a head 77 normally held clear of a fixed stop 78 by means of a spring 130

79. During a forward movement of the upper end of the hand-crank 70 to advance the platen, the other end of the plunger brings a cam surface 80 thereon into engagement with 5 a cam surface 81 of a one-way acting tappet or dog 82 which is mounted on the frame. The relative position of the dog 82 and the stop 78 is such that as the hand-crank 70 is swung with a quick motion, the plunger 10 will be projected by the dog 82, so that its head will engage the stop 78 before the spring 79 can return the plunger, which has cleared the dog 82, to its normal position. This will stop the hand-crank 70 so that 15 the operative knows then that the interleaved pack of work-sheets and carbon sheets is properly positioned for the initial line of writing. The dog 82 is pivotally mounted on a support 83, so that it will yield when 20 the abrupt face of the plunger 76 engages the abrupt face of the dog 82. A spring 84 will return the dog 82 to its normal position after the plunger 76 has escaped past the dog.

The work-sheets, and when typewriting 25 is going on the carbon sheets also, pass from the front side of the platen 1 to a guide-frame 85 and beneath a cutting-off knife 86. The knife 86 is adjustably mounted on a movable slide 87, so that it can be placed 30 at a number of positions with reference to a scale indicated by the numbers "5", "6" and "7", which may correspond to the number of lines in the bill or other piece of work. The adjustment is for the purpose 35 of varying the length of the work-sheet, such as a bill, and the numbers correspond to five, six and seven lines of typewriting. Normally, the knife 86 and its slide 87 are 40 in a raised position, corresponding to the position they occupy for cutting off the work-sheets. When, however, it is desired to catch hold of the pack of work-sheets to draw them around the platen by hand, this knife 86 is shifted down to the position of 45 Fig. 6. Inasmuch as such conditions are coincident with the requirement of releasing the pressure feed rolls 5 and 6, the slide 87 is operated from the release finger-piece 110 16.

50 For this purpose, the bell crank of the finger-piece is provided with an arm 88 connected to the slide 87 by a link 89. The link 89 and the arm 88 form a toggle with their pivotal point of connection on one 55 side of the line of centers, as in Fig. 5. When releasing the pressure rolls 5 and 6, the toggle is first straightened and then collapsed again to a greater distance to the Fig. 6 position, which will withdraw the 60 bail and knife to a position, permitting access to the leading edges of the work-sheets, as in Fig. 6. For steadyng the movement of the knife 86 and its slide 87, there are provided pinions 90 secured to 65 an axle mounted on the slide 87, and en-

gaging racks 91 on each side of the guide frame 85.

To gage the leading edges of the work-sheets as they are drawn from the platen before cutting them off with the knife 86, there is provided a gage 92 adjustably mounted by means of set screws 92^a (Fig. 5), on vertical extensions 93 of the guide frame 85. This gage 92 projects forwardly 70 from the face of the extensions 93 at both 75 its ends, and is connected between these projecting parts by a cross-bar 94 whose front face is below the front face of the projections.

The form of the gage 92 enables the 80 work-sheets to be properly squared as well as gaged, and also leaves room for a deflector 95 to be dropped beneath the projecting faces of the gage 92 for a gaging operation. Normally, this deflector is raised 85 to the full line position of Fig. 5, so as to clear the work-sheets from the gage as the typewriting goes on.

As the gaging operation takes place just 90 subsequent to the drawing forward of the work-sheets by hand, the deflector is permitted to recede when the pressure rolls 5 and 6 are released by the finger-piece 16. In other words, the deflector is mounted at 95 its lower end on guide-frame 85 and normally held in a raised position by a shifter 96 pivotally connected to a lever 97 and guided by extending through an opening in the frame 85. The tail end of the lever 100 97 engages a pin 98 provided on the slide 87, so that this slide when raised to its cutting-off position, which corresponds to the 105 normal typewriting position, will swing the deflector 95 to its effective full line position, Fig. 5.

When the knife 86 and its slide 87 are withdrawn for shifting of the work-sheets and catching the same, the pin 98 recedes, permitting the deflector 95 to fall to its ineffective dotted line position of Fig. 5.

The operation of the device will be readily understood when taken in connection 110 with the above description. If it is assumed that a piece of work, such as a bill, has just been completely written, the pack 115 of work-sheets and carbon sheets will occupy the position of Fig. 7, with the upper ends of the carbon sheets projecting onto the guide-frame 85.

In order to space the work-sheet strips 120 relative to the carbon sheets, to bring a fresh surface of the work-sheet strips in register with the active portion of the carbon sheets, it is first necessary to withdraw 125 reversely the pack comprising the assembled work and carbon sheets. For this purpose, the hand-crank 70, which is at this time near its foremost position, depending upon the length of the piece of work, must be forced rearwardly to the Fig. 6 position. 130

This motion of the hand-crank will rotate the platen 1 reversely, so as to move back the pack of work and carbon sheets, and at the same time will drive the feed rolls 19 5 and 20 reversely, so as to draw back on the work-sheet 17.

The gearing, it will be remembered, is also connected to the carbon rolls 29, so that they will be reversely driven to wind up 10 the carbon sheets 27. This continues until the hand-crank 70 comes to the limit of its movement, as in Fig. 6, when the carbon whole free stretch of sheets and the portion 15 of the work-sheets just previously written upon will be drawn straight out, in the rear of the guide-roll 72, so that there is no bend in them, and so that they are separated, minimizing the friction between the carbon sheets and the work-sheet strips 17. 20 The work-sheet strips may now be pulled forwardly to advance them relative to the carbon sheets. In the present case, this is done by hand; that is to say, the operative takes hold of the sheets and pulls them 25 around independently of the platen. In order to permit this relative movement between the platen and the work-sheets, the release-finger-piece 16 is depressed, which will disengage the pressure feed-rolls 5 and 30 6 from the work-sheets, and also, through the connecting linkage, shift the feed-roll 19 out of coöperative relation with the feed-roll 20. The dog 66 also acts at this time to lock the train of gearing from the platen 35 to the feed-rolls 19 and 20 and carbon rolls 29, thus enabling the work-sheet strips to be drawn forward while the carbon sheets remain stationary.

As the sheets may occupy somewhat the 40 position of Fig. 6, it is necessary to withdraw the knife 86 from its Fig. 7 position to its Fig. 6 position. This is taken care of at the same time that the feed-rolls are released, by the finger-piece 16. This action, as explained above, also depresses the deflector 45 95, permitting access to the gage 92. The operative then grasps the top edges of the projecting work-sheets 17 and draws them up until the leading edges engage the gage 50 92. This gage has been previously adjusted with an adjustment of the knife 86, corresponding to the length of work-sheet desired. The release finger-piece 16 may then be restored to its normal position, unlocking 55 the train of gearing, bringing the pressure feed-rolls 5, 6, 19 and 20 into play, and restoring the knife-blade 86 to its normal raised position. The pack of sheets may then be warped across the edge of the knife- 60 blade, severing the projecting portions of the strip 17, bearing one piece of work, such as a bill. The restoration of the finger-piece 16 also raised the deflector 95 to its normal full-line position, Fig. 5, so that in type- 65 writing subsequently, the leading edges of

the work-sheets will be guided over and beyond the gage 92.

Inasmuch as the work-sheet strips have been drawn beyond the carbon sheets a distance of the length of the piece of work, such 70 as a bill, the carbon and work-sheet strips may now be advanced as a unit from the Fig. 6 position to a position such that the first line to be written on, backed up by carbon sheets, will come to the printing 75 point 73.

To effect this advancement, it is merely necessary to swing the hand-crank 70 forward with a rather quick motion, when the plunger 76 will be automatically thrown out 80 to temporarily engage the stop 78, thus bringing the hand-crank to a stop. The plunger is so located, as before described, that it will limit temporarily the rotation of the platen, the feed-rolls 19 and 20 and 85 the carbon rolls 29 an extent sufficient to feed the pack of assembled sheets from the point 75 (Fig. 6), to the point 73 (Fig. 7).

The type-bars 74 can now be operated to write the new piece of work, and the platen 90 spaced, line by line, by means of the line-space lever 4. This movement will also drive the feed-rolls 19 and 20 and the carbon rolls 29, enabling the work-sheet strips 17 and the carbon sheets 28 to move along at all points 95 at substantially the same speed, thus eliminating any drag which might tend to displace the sheets relative to the platen.

When the piece of work is finished, the parts again come to the position, Fig. 7, and 100 the pack of assembled work and carbon sheets may once more be withdrawn to straighten out the bend and eliminate friction between the carbon and work-sheets. Then the work-sheets are pulled forward 105 relatively to the carbon sheets to get the required spacing, and the pack once more brought to the printing point for still another piece of work. Thus, the same sheets of carbon paper can be used repeatedly with 110 different sections of continuous strips of work-sheet until the carbon sheets are worn out, when they can be replaced by removing the carbon rolls 29.

When the work-sheet and carbon sheets 115 are retracted to permit the relative movement of the work-sheet to the carbon sheets, the first line of writing on the last written form is moved rearwardly away from the platen and is located directly above the 120 roller 72, as seen in Fig. 6.

In order that the work-sheets, when thus retracted, will not be moved out of the bite of the feed rolls, a surplus amount of work-sheet is always left on the web. That is to 125 say, there are always two forms either previously written on or left blank still attached to the form being written upon. This is done, because, if the form written upon was severed immediately after being fin- 130

ished, the work-sheet when retracted would be moved out of the bite of the feed rolls, and would therefore have to be re-inserted in the machine. These extra forms permit the operator to grip the work-sheet at a convenient place on the machine; that is, away from the platen.

The carbon paper on the rolls 29 is of sufficient length to extend from the roll 10 around to the platen and up to the highest point to which a form is fed while being typewritten upon.

When the carbon sheet has been worn out, a new carbon sheet may be attached to the 15 roll 29, or the carbon sheets may be supplied upon rolls; and in that case, the old roll may be removed as above described, and the new roll placed in the machine. It is not necessary that the entire carbon sheet be 20 carbonized, as the only part that is necessary to be carbonized is the part that actually is in register with the form which is being written upon. The remainder may be 25 of cloth or of a different quality of paper.

Guide-plates 23 to 26 may each be formed 30 integral with a pair of bosses 100 which are provided with openings 101. The guide-plates may be mounted on the frame 30 by being slid onto pins 102 secured to the frame 35 of the machine. These pins can be of such length as to accommodate any number of guide-plates 24; the pins in the drawings being shown as sufficient to accommodate two guide-plates. However, it will be understood 40 that any number of guide-plates may be placed on each side of the web, according to the number of folds in the web, or the 45 number of separate sheets used.

It will be understood that the drawings 40 are diagrammatical, certain parts being exaggerated with relation to other parts, for the sake of clearness; for instance, the wide spacing apart of the carbon sheet-guides 23 to 26. This has been done for the sake of 45 illustrating the manner in which the web is interleaved with the carbon sheets, and it will be understood that no such spacing is necessary, or, in fact, desirable, as it is 50 inconvenient, especially where fan-folded sheets are used, to spread the separate folds any considerable distance. The same applies to other parts of the machine which have been exaggerated in proportions for 55 the sake of clearness.

55 Variations may be resorted to within the scope of the invention, and portions of the improvements may be used without others.

Having thus described my invention, I claim:

60 1. The combination with a typewriter carriage including a platen adapted to support a plurality of work-sheet strips passed around the platen, and extending substantially horizontally rearwardly therefrom, of 65 a substantially horizontal guide having a

guiding edge arranged at angles to the line of travel of said work-sheet strips to the platen, for directing one or more carbon sheets from points off to one side of said work-sheet strips to positions in between 70 said work-sheet strips, whereby a pack of intermingled work and carbon sheets may be fed to said platen, and a substantially horizontal rearwardly-extending frame carrying said guide, attached to said carriage 75 and adapted to form a table for supporting the whole free stretch of carbon sheet.

2. The combination with a typewriter carriage including a platen arranged to support a plurality of work-sheet strips extending substantially horizontally to said platen from a point somewhat in the rear thereof, of a substantially horizontal guide located 80 between said strips, arranged to warp carbon sheets so as to change their direction of travel from that at right angles to the direction of travel of said work-sheet strips to a direction of travel in parallel with the direction of travel of said work-sheet strips, thereby interleaving said carbon sheets 85 between said work-sheet strips, and a substantially horizontal rearwardly-extending frame carrying said guide, attached to said carriage and adapted to form a table for supporting the whole free stretch of carbon 90 sheets.

3. The combination with a typewriter carriage including a platen arranged to support a plurality of work-sheet strips and carbon sheets wrapped around the platen, 100 and extending substantially horizontally and rearwardly therefrom, of a plurality of substantially horizontal guides, having their guiding edges arranged at angles to the direction of travel of said work-sheet strips, 105 and at angles to each other, whereby some of said carbon sheets may be directed from one side, and others of said carbon sheets directed from the other side, of the work-sheet strips to a position in between said 110 work-sheet strips, and extending in the same general direction as said work-sheet strips, and a substantially horizontal rearwardly-extending frame carrying said guides, attached to said carriage and adapted to form 115 a table for supporting the whole free stretch of carbon sheets.

4. The combination with a typewriter carriage including a platen arranged to support a plurality of work-sheet strips wrapped around said platen, and extending substantially horizontally and rearwardly therefrom, of a plurality of substantially horizontal guides located between said work sheet strips, and having guiding edges extending at angles to the direction of travel of said work-sheet strips, and at right angles to each other in alternation, so as to deflect carbon sheets from traveling from 125 positions at the side of said work-sheet 130

- strips toward and between said work-sheet strips to a direction of travel in parallel with the direction of travel of said work-sheet strips, and a substantially horizontal 5 rearwardly-extending frame carrying said guides, attached to said carriage and adapted to form a table for supporting the whole free stretch of carbon sheets.
5. The combination with a platen arranged to manipulate a plurality of work-sheet strips wrapped around the platen, and extending rearwardly therefrom, of a plurality of rolls for supporting carbon sheets, said rolls being located in pairs on opposite 10 sides of said work-sheet strips, and offset vertically and horizontally from each other to minimize space, and guiding plates located between said work-sheet strips, and having guiding edges alternating in their 15 angularity with respect to each other and the direction of travel of said work-sheet strips, so as to turn the carbon sheets from traveling in directions at right angles to the line of travel of said work-sheet strips to 20 lines of travel in parallel with the lines of travel of said work-sheet strips.
6. The combination with a platen arranged to manipulate and support a plurality of work-sheet strips, wrapped around 25 said platen, and extending substantially horizontally rearwardly therefrom, of a roll for a carbon sheet to be interleaved between said work-sheet strips, said roll placed to the side of the path of the strips, a guide 30 for bringing the carbon sheet between the work-strips, and direct driving means for said platen and said roll, acting simultaneously, enabling the positive feeding of said carbon sheet at both ends.
- 40 7. The combination with a typewriter carriage including a platen arranged to manipulate and support a plurality of work-sheet strips in a pack, wrapped around said platen, and extending substantially horizontally and rearwardly therefrom, of a pair of feed rolls for said work-sheet strips, gripping the work-sheet strips between them at a point along a horizontal stretch distant from said platen, so as to feed said 45 strips by a drive at the platen and at the point distant from the platen, and driving means connecting said platen and said feed rolls to rotate in unison, so that the work-sheet strips may have substantially the same travel at the platen and at a point distant from the platen.
- 50 8. The combination with a platen arranged to support and manipulate a plurality of work-sheet strips, wrapped around said platen, and extending rearwardly therefrom, of feed rolls, gripping said work-sheet strips at a point distant from the platen, to assist the platen in manipulating said work-sheet strips, pressure feed rolls at the platen for assisting 55
- the platen in manipulating the work-sheet strips, and a release for concomitantly silencing said feed rolls at the platen, and said feed rolls at a point distant from the platen, so that said work-sheet strips can 70 be drawn by hand around said platen and through said feed rolls at the point distant from said platen.
9. The combination with a platen arranged to support and manipulate a plurality of work and carbon sheets, of feed rolls for said sheets at the platen, feed rolls for said work-sheets at a point distant from the platen, rolls for said carbon sheets at a point distant from the platen, and a common drive for said platen, said work-sheet feed rolls and said carbon rolls, whereby the work and carbon sheets may be fed positively at the platen and at separate points distant from the platen.
10. The combination with a platen arranged to support and manipulate a plurality of work-sheet strips and carbon sheets, of rolls for said carbon sheets, a positive driving connection between said platen and said rolls, whereby said carbon sheets may be fed at both ends simultaneously, and means for locking said drive against rotation, to enable said work-sheets to be drawn while said carbon sheets are held 90 stationary, to enable a relative spacing between said work-sheet strips and said carbon sheets.
11. The combination with a platen arranged to support and manipulate a pack of interleaved carbon sheets and work-sheet strips, of feed rolls for assisting said platen in manipulating said work-sheets, rolls for said carbon sheets, a positive common driving connection for said platen and said carbon rolls, and means for concomitantly releasing said feed-rolls and locking said drive to prevent a rotation of said carbon rolls, whereby said work-sheet strips may be drawn on to advance them relative to said 100 carbon sheets held stationary.
12. The combination with a platen arranged to support and manipulate interleaved work-sheet strips and carbon sheets, of feed rolls coöperating with said platen at the point to manipulate said strips and sheets, feed rolls coöperating with said platen at a point distant from said platen to manipulate said work-sheet strips, carbon rolls coöperating with said platen at a point 115 distant from the platen to manipulate said carbon sheets, a drive common to said platen and said distant feed rolls and said carbon rolls, and means for simultaneously silencing all said feed rolls and locking said 120 drive, so as to hold said carbon sheets stationary, and permit said work-sheet strips to be drawn on by hand to space them relative to said carbon sheets.
13. The combination with a platen ar- 130

- ranged to support and manipulate a plurality of work-sheet strips and carbon sheets, of rolls for said carbon sheets, placed off to one side of the work-sheet strips, 5 guiding means for interleaving and directing said carbon sheets between and in the direction of said work-sheet strips, a pinion for each of said carbon rolls, a rack for the pinions and carbon rolls on one side of 10 said work-sheet strips, a second rack for the pinions and carbon rolls on the opposite side of said work-sheet strips, and driving means for extending and retracting said racks in opposite directions with respect to 15 each other, so as to rotate said carbon rolls alternately in opposite directions, to enable them to be fed from opposite sides between said work-sheet strips to the platen, and later withdraw them from the platen.
- 20 14. The combination with a platen arranged to support and manipulate a pack of work-sheets strips and carbon sheets, of rolls for said carbon sheets, placed on both sides of said work-sheet strips, oppositely 25 facing racks for driving said carbon rolls, a pinion located between said racks for driving them simultaneously in opposite directions, and a driving train from said pinion to said platen, enabling the carbon rolls 30 and the platen to rotate in unison.
15. In a typewriting machine, the combination with a revoluble platen, of feed rolls for causing work-sheets to travel with said platen, a carbon-paper-holder adapted 35 to hold carbon sheets as they approach the platen, a second set of feed rolls adapted to engage the work-sheets before they reach the carbon sheets, and means for simultaneously making all said feed rolls ineffective 40 to hold work-sheets.
16. In a typewriting machine, the combination with a revoluble platen, and feed rolls for holding work-sheets against the platen, of a carbon-paper-holder adapted to 45 feed carbon sheets to the platen, means for throwing off said feed rolls from the platen, and means operated by said throwing-off means for locking the carbon-paper-holder to prevent travel of the carbon sheets.
- 50 17. In a typewriting machine, the combination with a revoluble platen, and a device for holding work-sheets against the platen, of a gage for adjusting work-sheets when said holding device is ineffective, a 55 knife for severing work-sheets after being adjusted against the gage, a normally effective deflector for carrying sheets past said gage, and means for making said holding device and said deflector simultaneously 60 ineffective.
18. In a typewriting machine, the combination with a revoluble platen, of feed rolls for holding work-sheets against said platen, a knife behind which a web passed 65 around the platen is adapted to feed, and means for simultaneously casting off the feed rolls and withdrawing said knife to a position to permit the web to be seized.
19. The combination with a platen arranged to support and manipulate one or 70 more continuous strips of work-sheets, of a knife located to enable the strips of work-sheets to be cut off flush therewith after each individual bill or other piece of work is completed, pressure rolls coöoperating with 75 said platen to manipulate said work-sheet strips, and a common means for releasing said pressure rolls and withdrawing said knife-blade from position flush with the loose ends of said work-sheet strips, whereby 80 said work-sheet strips may be grasped at their loose ends and pulled around said platen.
20. The combination with a platen arranged to support and manipulate one or 85 more continuous strips of work-sheets, of a knife located to enable the strips to be cut off flush with the knife after the pieces of work have been completed, said knife being 90 slidingly mounted, and a toggle mechanism for withdrawing said knife to uncover loose ends of said work-sheet strips, permitting them to be grasped and acting also to restore said knife to a cutting-off position.
21. The combination with a platen arranged to support and manipulate one or 95 more work-sheet strips, of pressure rolls coöoperating with said platen to manipulate said work-sheet strips, releasing means for said rolls, enabling the work-sheet strips to 100 be drawn around said platen by hand, a gage for determining the extent of this hand-spacing of the work-sheet strips, a deflector for clearing the leading edges of said work-sheet strips from said gage during a 105 typewriting operation, and means for causing the withdrawal of said deflector to an ineffective position when said pressure rolls are released, so as to permit the coöperation of the work-sheet strips with said gage to 110 determine the length of the work-sheet.
22. The combination with a platen arranged to support and manipulate one or 115 more work-sheet strips, of feed rolls coöoperating with said platen to manipulate said strips, a knife for cutting-off said strips in lengths corresponding to the desired lengths of the individual pieces of work, a gage for said work-sheet strips, a deflector for guiding said strips around said 120 gage during a normal typewriting operation, and means for concomitantly releasing said rolls, withdrawing said knife to permit access to the leading edges of said work-sheet strips, and silencing said deflector so 125 that the work-sheet strips can be drawn by hand around the platen and to a position with their leading edges contacting with said gage.
23. The combination with a platen, of 130

feed rolls for said platen arranged to co-operate with and manipulate one or more continuous strips of work-sheets, a knife for enabling said work-sheet strips to be cut off 5 in lengths, leaving the strips with their free ends flush with said knife, means for withdrawing said knife to uncover the leading edges of said strips to permit access thereto, and justifying means for forcing said knife 10 to move evenly on both sides.

24. The combination with a platen arranged to support and manipulate one or more continuous work-sheet strips, of a gage for said strips, a deflector for clearing the 15 strips to guide them past the gage, a lever connected to manipulate said deflector, and a slide engaging said lever to manipulate said deflector.

25. The combination with a platen arranged to support and manipulate a pack 20 of interleaved work-sheets and carbon sheets, of sheet-driving means for withdrawing said work-sheets and carbon sheets reversely from said platen to straighten the same out and 25 enable a relative spacing of said work-sheets relative to said carbon sheets, a gage for determining the extent of this spacing, said gage also determining the length of the sheet, and a knife-blade for cutting off the 30 sheets as gaged from the continuous strips.

26. The combination with a platen arranged to support and manipulate a pack of interleaved work-sheets and carbon sheets, of sheet-driving means for withdrawing said 35 work-sheets and carbon sheets reversely from said platen to straighten the same out and enable a relative spacing of said work-sheets relative to said carbon sheets, a gage for determining the extent of this spacing, said 40 gage also determining the length of the sheets, a knife-blade for cutting off the sheets as gaged from the continuous strips, and means for adjusting both said knife and said gage to vary the length of the sheets.

45. 27. The combination with a typewriter carriage including a platen arranged to support and manipulate a manifold horizontal web interleaved with carbon sheets curved therearound, of substantially horizontal triangular guide-plates for directing the carbon sheets to positions between the folds of said web, so that the whole free stretch of carbon sheets may lie along a substantially horizontal reach thereof, and supports being 50 hind the carriage for said guide-plates holding said guide-plates in alternation at separate points so that said guide-plates have alternate apices projecting toward each other and freely between the successive folds of 55 said manifold web, whereby the carbon sheets will be guided between the folds of said web and still permit the traveling movement of the web relative to the guide-plates.

60. 28. The combination with a platen arranged to support a pack of interleaved

work-sheets and carbon sheets, of means for feeding said work-sheets controlled by the rotation of the platen, means for withdrawing the work-sheets to permit the shifting of the work-sheets relative to the carbon 70 sheets, and means for withdrawing the carbon sheets concomitantly with the withdrawal of the work-sheets, but transversely thereto to bring the carbon sheets to the side of the work sheets. 75

29. In a typewriting machine, the combination with means for guiding superposed webs and carbon sheets into the machine, of a revoluble platen around which the superposed webs and carbons advance, said guiding means and said platen being arranged so that the webs pursue a normal tortuous course which causes the carbon sheets to be bound between the webs, and means for withdrawing together from the platen to a 80 straight line both the carbon sheets and the portion of the web adjacent thereto, and thereby releasing the carbon sheets from such interbinding, said last-named means also adapted to move the carbon sheets out of 85 superposed relation with the webs.

30. In a typewriting machine, the combination with means for guiding superposed webs and carbon sheets into the machine, of a revoluble platen around which the superposed webs and carbons advance, said guiding means and said platen being arranged so that the webs pursue a normal tortuous course which causes the carbon sheets to be bound between the webs, means for withdrawing from the platen to a straight line both the carbon sheets and the portion of the web adjacent thereto, and thereby releasing the carbon sheets from such interbinding, said last-named means also adapted to move 90 the carbon sheets out of superposed relation with the webs, and means for holding the carbon sheets displaced with relation to the platen, and simultaneously permitting the web to be moved by hand relative to the 95 platen, so as to bring the fresh portion of the web into co-operative relation with the carbon sheets, so that when the new portion of the web is replaced to the platen, the carbon sheets and the web will be properly interposed. 100

31. In a typewriting machine, the combination with a platen arranged to support and feed a pack of interleaved work-sheets and carbon sheets, of means for guiding the work-sheets to the platen, said guiding means and said platen being so arranged that the carbon sheets are bound between the work-sheets, means for relieving the binding action of the carbon sheets and 120 work-sheets, stationary means for withdrawing said work-sheets for this purpose, and means for retracting the carbon sheets 125 transversely to the work sheets as the work-sheets are being withdrawn from the platen. 130

32. In a typewriting machine, the combination with a platen arranged to support a plurality of superposed work-sheets and carbon sheets, the course of the sheets being such as to cause the work-sheets and carbon sheets to bind, of means for feeding said work-sheets with said platen line by line in the ordinary course of typewriting, a driver for withdrawing the work-sheets and the carbon sheets from the platen when the desired work has been completed to relieve the bound sheets, and means for locking the carbon sheets in withdrawn position and simultaneously permitting the work-sheets to be drawn around the platen independently thereof, and independently of the carbon sheets for spacing the work-sheets relative to the carbon sheets.
33. In a typewriting machine, the combination with a platen arranged to support a plurality of superposed work-sheets and carbon sheets, the course of the sheets being such as to cause the work-sheets and carbon sheets to bind, of means for feeding said work-sheets with said platen line by line in the ordinary course of typewriting, a driver for withdrawing the work-sheets and the carbon sheets from the platen when the desired work has been completed to relieve the bound sheets, means for locking the carbon sheets in withdrawn position and simultaneously permitting the work-sheets to be drawn around the platen independently thereof, and independently of the carbon sheets for spacing the work-sheets relative to the carbon sheets, and means for effecting a predetermined, continuous feed of the platen, the work-sheets and the carbon sheets, to bring to printing position the leading edge of the new portion of the work-sheets.
34. In a typewriting machine, the combination with a platen arranged to support a plurality of superposed work-sheets and carbon sheets, the course of the sheets being such as to cause the work-sheets and carbon sheets to bind, of means for feeding said work-sheets with said platen line by line in the ordinary course of typewriting, a driver for withdrawing the work-sheets and the carbon sheets from the platen when the desired work has been completed to relieve the bound sheets, means for locking the carbon sheets in withdrawn position and simultaneously permitting the work-sheets to be drawn around the platen independently thereof, and independently of the carbon sheets for spacing the work-sheets relative to the carbon sheets, and means for effecting a predetermined, continuous feed of the platen, the work-sheets and the carbon sheets, to bring to printing position the leading edge of the new portion of the work-sheets, said means being arranged to become ineffective to determine the position of the platen after said predetermined, continuous feed operation has been completed to permit the web to be fed line by line during the usual course of typewriting.
